(57) **CLAIM**

The ornamental design for a bath bomb, as shown and described.

DESCRIPTION

FIG. 1 is a top perspective view of a bath bomb showing our new design;

FIG. 2 is a bottom perspective view thereof;

FIG. 3 is a top view thereof;

FIG. 4 is a bottom view thereof;

FIG. 5 is a front view thereof;

FIG. 6 is a front left side view thereof;

FIG. 7 is front right side view thereof;

FIG. 8 is a back left side view thereof; and,

FIG. 9 is a back right side view thereof.

The broken lines in the figures are for the purpose of illustrating portions of the bath bomb, which form no part of the claimed design.

1 Claim, 9 Drawing Sheets
